UNITED STATES PATENT OFFICE.

ROCCO RECATTI, OF ST. LOUIS, MISSOURI.

FIGURE WHEELED TOY.

Application filed February 2, 1925. Serial No. 6,186.

To all whom it may concern:

Be it known that I, Rocco RECATTI, a subject of the King of Italy, and resident of the city of St. Louis and State of Missouri, have invented certain new and useful Improvements in Figure Wheeled Toys, of which the following is a specification containing a full, clear, and exact description, reference being had to the accompanying drawings, forming a part thereof.

My invention relates to improvements in toys and has for its primary object a toy which is designed to be propelled along the floor by means of a spring motor and on which are mounted a plurality of figures, which, when the device is operated, have motion imparted thereto.

A further object is to construct a toy of the spring motor driven type which is provided with a pair of animals adapted to be placed in motion by the driving mechanism so as to have the appearance of being engaged in a fight, and also a figure of a human being which appears to be attempting to separate them.

In the drawings:

Fig. 1 is a side elevation of my device with one side thereof removed showing the operating mechanism;

Fig. 2 is a vertical cross section with the upper part of the figures broken away; and

Fig. 3 is a vertical fragmental section of the fore legs of one of the animals showing the method of jointing the same.

In the construction of my device I employ a carriage having a top 4, and side members 5. Extending through the side members and adjacent the rear end thereof is a shaft 6. This shaft projects beyond the sides and has secured to its ends driving wheels 7. The shaft 6 is also provided intermediate its ends with a crank 8 to which is attached a rod 9. The rod 9 extends through an opening 10 formed in the top of cover 4. Mounted on the upper end of the rod 9 is a human figure 11 which is provided with a pivoted arm 12, the hand 13 of which is shown as grasping a stick or whip 14.

Extending through the sides 5 is a shaft 15 on which is mounted a drum 16. Secured to one end of the drum 16 is a gear 17 which is provided with a plurality of extensions 18. These extensions extend inwardly and at right angles to the face of the gear 17. Surrounding the drum 16 is a coil spring 19, one end of which is se-

cured in the drum 16, the opposite end 20 is secured to a ratchet 21 which is mounted on the shaft 15. The ratchet 21 is designed to be turned by means of a key 22 thus causing the spring 19 to be wound around the drum.

Extending through the sides 5 is a shaft 23 on which is mounted a pinion 24 which meshes with the gear 17. The shaft 23 has also mounted thereon a gear 25 which in turn meshes with a pinion 26 which is secured to the shaft 6. Carried by the sides 5 is a shaft 27 on which is pivotally mounted a lever 28. The lever is so arranged that its short arm 29 is in the path of travel of the projections 18, the long arm 30 is provided with an outwardly extending stud 31, and pivotally secured to this stud is one end of the levers 32, these levers extend through openings 33 formed in the top 4. The top 4 is also provided with ears 34 to which the hind legs 35 of the animals 36 are pivotally secured. The fore legs of the animals consist of the portions 37 and 38, these portions are pivotally joined at the knee. The one leg by means of a rivet 39, and the other leg by means of the portion 40 which is formed by bending the upper end of the levers 32 at right angles to each other.

Adjacent the forward part of the carriage is a guide wheel 41 which is so mounted that it can be adjusted and thereby cause the carriage to travel either straight ahead or in a circle.

The operation of my device is as follows:

After being assembled the spring 19 is wound by means of the key 22 and the device placed on the floor, the unwinding of the spring 19 sets in motion the train of gears causing the axle 6 to rotate and drive the wheels 7 moving the carriage across the floor. During the rotation of the gears the projections 18 come in contact with the arm 29 of the lever 28 depressing it and raising the arm 30. This raising causes the levers 32 to be moved upwardly through the openings 33 and by reason of the hind legs of the animals 36 being pivoted, the animals appear to rear upwardly and backwardly. The front legs, however, being pivoted at the knee permit the lower portion of these legs to remain in a vertical position thus giving a life-like appearance to the animals.

Upon the projections 18 passing the end of the arm 29 the lever is permitted to re-

turn to its starting position, this allows the animals to drop on their fore legs and in so doing bump their heads together giving them the appearance of fighting.

5 During this movement the crank 8 causes the lever 9 to rise and fall and also oscillates backward and forward, this movement causes the arm 12 to swing and gives the figure 11 the appearance of jumping forward and backward and at the same time attempting to separate the animals by means of the stick or whip which he carries.

Having fully described my invention, what I claim is:

- 15 1. A toy comprising a carriage, a spring motor, a train of gears and wheels for driving said carriage, a lever pivoted intermediate its ends carried by said carriage, projections formed on one side of one of said gears and adapted to contact with one end of said lever whereby said lever is intermittently rocked and the opposite end of said lever suddenly raised and lowered, a top for said carriage, a plurality of animals pivotedly secured at their hind legs to said top, and a lever mechanism secured to said animals and the pivoted lever for suddenly raising and lowering the fore part of said animals during the operation of said motor.
- 20 2. A toy comprising a carriage, a spring motor, a train of gears and wheels for driving said carriage, a top for said carriage, a pivoted lever, projections formed on the side of one of said gears and adapted to
- 25 contact with one end of said pivoted lever during the rotation of the gears whereby the opposite end of said lever is intermittently raised and lowered during the rotation of said gear, a plurality of animals pivotedly secured at their hind legs to said top, a lever mechanism secured to said animals and operated by the pivoted lever for raising and lowering the fore part of said animals dur-

ing the operation of said motor, a human figure having pivoted arms located adjacent said animals, and a connection between the driving mechanism and said figure for moving the same up and down and forward and backward, said movement causing the arms of the figure to swing.

50 3. A toy comprising a carriage having a top and sides, an axle having a crank formed therein extending through said sides, driving wheels secured to the ends of said axle, a pinion secured on said axle, a rod having one end pivotally secured to said crank, the other end projecting through the top of the carriage, a human figure provided with a pivoted arm mounted on the free end of said rod, a drum located within said carriage, a gear carried by said drum, projections formed integral with one face of said gear, a lever pivotally mounted intermediate its ends located in said carriage and having one end thereof in the path of travel of said projections whereby said lever is rocked, a pair of animal figures pivotally secured at their hind legs to the top of said carriage, the fore legs of said animals being pivoted at the knee, a lever secured at one end to the pivot point of one fore leg of each animal and extending through the top of said carriage, the opposite ends of said levers being pivotally connected to the free end of the pivoted lever, a coil spring carried by said drum, means for winding said spring for placing the gear carried by the drum in rotation, a train of gears interposed between the last mentioned gear and the pinion on the axle for rotating said axle and wheels, and a guide wheel pivotally secured to said carriage adjacent its forward end for regulating the path of travel of said carriage.

55 In testimony whereof, I have signed my name to this specification.

ROCCO RECATTI.
